UNITED STATES PATENT OFFICE

2,530,347

SELECTOR MECHANISM FOR AUTOMATIC PHONOGRAFS

Lloyd J. Andres, Itasca, Ill., assignor, by mesne assignments, to H. C. Evans & Company, Chicago, Ill., a corporation of Illinois

Application August 17, 1946, Serial No. 691,197

4 Claims. (Cl. 274—10)

1

In prior selectors in which a self-restoring construction has been employed, the structure has been quite complicated and has involved serious difficulties both in manufacture and in operation. The elements have necessitated precise manufacture and adjustment and many more parts have been required than in the present construction. Furthermore, the problem of removing individual elements which might require repair or replacement has been a difficult one, since the individual elements could not be separately removed and the removal and replacement required great skill and often the complete disassembly of the mechanism. From the standpoint of operation the prior mechanisms have been relatively uncertain in action and have been limited to comparatively slow speeds of the selector drum (to be hereinafter described). For example, prior constructions have been limited to drum speeds on the order of ten revolutions per minute, whereas the device of the present invention is capable of positive restoration at drum speeds on the order of two hundred revolutions per minute.

The principal object of the present invention is to provide a selector mechanism which overcomes these manufacturing and operational problems and which is much more simple in construction and efficient in operation.

One of the more specific objects of the invention is to provide in a self-restoring latch construction shock absorbing means which will not only protect the mechanism from undue strain but will render more certain the reengagement of the latch elements in the self-restoring operation. Other objects and advantages of the invention will be apparent from the following description, taken in connection with accompanying drawings, in which:

Fig. 1 is a fragmentary plan view of the part of the phonograph mechanism in which the invention is contained;

Fig. 2 is a sectional view taken substantially on the section line 2—2 of Fig. 1;

Fig. 3 is a detailed elevational view of certain of the elements shown in Fig. 2 taken from the left hand side of the latter figure;

Fig. 4 is a view similar to Fig. 2 with the elements shown in different position; and

Fig. 5 is a like view with the elements shown in still another position.

In the illustrative embodiment of the invention shown in the drawings, the elements of the mechanism are supported by side frames 1, an upper frame element 2, and a lower frame element 10 55

(see Fig. 2), the frame also including a container 3 for a bank of electromagnets to be later mentioned.

A selector drum 4 is journaled in operating relationship with the frame 1 and is provided with a series of lugs 5 helically arranged about its outer surface. This drum is adapted to be driven by means not shown and the lugs 5 thereon coat with the selector latches to be described later.

An operating crank 6 is pivotally suspended from the frame members 1 on pivots 7 and is so arranged that it will be actuated upon operation of any one of the selector latch devices, of which 15 a considerable number are arranged between the frame members 1.

One of the latch units is shown in Figs. 2-5 inclusive, of the drawings, it being understood that the other units are of the same construction and that the number of such units will correspond in number and position to the number of lugs 5 on the selector drum 4.

The principal latch elements are positioned in slots 8 and 9 (see Fig. 2) in the upper and 25 lower frame elements 2 and 10, respectively. Said elements 2 and 10 are positioned parallel to each other and are supported by and between the frame members 1, 1 shown in Fig. 1.

Operating latches 11 are pivotally supported 30 on upper cross member 2 by a rod 12 mounted in fixed position in said cross member. An open notch 13 is provided in a head portion of the latch 11 to permit movement and removal of said latch as hereinafter described.

Tripping latches 14 are pivoted on a rod 15 integral with lower frame member 10, and, like the operating latches 11, are provided with open slots 16 to facilitate removal and replacement and to permit other movement as hereinafter described. A plurality of individual magnets 17 are so positioned in frame element 3 that the pole pieces thereof will individually act upon armature members 18 secured to latches 14, as shown in Figs. 2, 4 and 5.

Spring 19, having their opposite ends secured to the latches 11 at 20 and to the latches 14 at 21 are provided for holding said latches 45 yieldingly in engagement with the pivot pins 12 and 15 respectively. A working end 26 of the latches 14 is normally held by the spring 19 in engagement with a mating abutment 27 on the head portion of the latches 11.

A tripping crank 22, pivotally mounted at 23 in the end plates 1, is positioned in the path of movement of extensions 24 of the latches 11.

as shown in Fig. 2 and a bearing rod 25 is rigidly secured to the member 10 in the path of movement of said extensions 24.

Fig. 3 illustrates the position of the spring 19 in relation to the latches 11 and 14 and their relation to the frame members 2 and 10.

The operation of the mechanism is as follows:

Referring to Fig. 2, which shows all elements in their normal rest position, the working end 26 of the latch 14 is held in engagement with a mating abutment 27 on the latch 11 by the force exerted between the said latches by the spring 19. In this rest position the working end 28 of the extension 24 of the latch 11 is held out of the path of movement of corresponding lug 5 on the drum 4.

Referring to Fig. 4 showing the condition when the magnet 17 has been momentarily energized, the tripping latch 14 will have been moved to the position shown because of the attraction of the armature 18 by the magnet 17, which overcomes the normal tension of the spring 19. Under these conditions, the operating latch 11 will have moved to the position shown, also by the action of spring 19, and in so doing will have moved the crank 22 about its pivot 23, which latter movement is normally used to start rotation of the drum in the direction shown by arrow through the medium of a motor (not shown). At this time the working end 28 of latch 11 will have moved into the path of its corresponding lug 5 on said drum 4.

The next function of the device is illustrated in Fig. 5 wherein the lug 5, in moving with the drum 4 in the direction shown by arrow, will have engaged the working end 28 of the latch 11, which latch will thus have been moved against the restraining action of spring 19 to an upper position as shown, being guided in this movement by the rods 12 and 25. This upward movement of latch 11 is made possible by the clearance in slot 13. Thus, a second function of the selector is accomplished by moving crank member 6 about its pivot 7 to perform a selecting operation in other mechanism (not shown).

When the elements are in the position as shown in Fig. 5, it will be noted that the latch abutment 27 has moved upward sufficiently far to provide for re-engagement with the working end 26 of the latch 14. This re-engaging movement is the result of the camming action of the rod 25 against one surface of the working end of the latch 11. The restoring action of the device is completed when lug 5 disengages the working end 28 of the extension 24 of the latch 11, which permits the spring 19 to restore said latch 11 and the latch 14 to their initial positions shown in Fig. 2.

It will also be noted that the disengagement of said working end 28 of the latch 11 from the lug 5 is accompanied by a shock engagement of the abutment 27 and the working end 26 of the latch 14. In previous selectors no provision was made to absorb this shock, whereas in the present construction, due to the slotted end 16 engaging the rod 15, momentary movement under the influence of spring 19 in a downward direction takes place, thus avoiding undue shock and eliminating the possibility of disengagement of the working end 26 of the latch 14 from the abutment 27.

It will be apparent that either or both of the latch elements 11 and 14 may be removed and replaced, without disturbing any other parts of the device, by manually unhooking the slotted

ends of the latches 11 and 14 from rods 12 and 15, respectively. The latches may then be moved outwardly, together with spring 19, from the cross members 2 and 10, thus fulfilling one of the principal objects of the invention.

The simplicity of the construction will also now be evident, comprising, as it does, essentially only the two self-restoring latches 11 and 14 for performing all the functions heretofore performed by much more complicated and less efficient mechanism.

The foregoing detailed description has been given for clearness of understanding only, and no unnecessary limitations should be understood therefrom but the appended claims should be construed as broadly as permissible in view of the prior art.

I claim:

1. In combination with a selector drum and a selector-actuated element of an automatic phonograph, selector mechanism comprising a support, an operating latch pivotally connected to said support and having a working part movable into the path of an actuating lug on said selector drum and a part arranged to actuate said selector-actuated element of the phonograph when force is applied to said first-mentioned part by said actuating lug, an abutment on said operating latch, a tripping latch pivotally connected to said support by a pin-and-slot connection, permitting lineal as well as pivotal movement of such latch, and having a working part normally engaging said abutment on the operating latch, means for operating the tripping latch to disengage the same from said operating latch, and means for thereupon moving said operating latch into the path of said lug, the operating latch being movable by the lug to a position in which it is disengaged by the latter and in which the abutment thereon is automatically re-engageable by said working part on the tripping latch upon disengagement of the operating latch by said lug, said tripping latch being movable lineally by said operating latch, in shock absorbing motion, upon re-engagement of said abutment with said working part.

2. In combination with a selector drum and a selector-actuated element of an automatic phonograph, selector mechanism comprising a support, an operating latch pivotally connected to said support and having a working part movable into the path of an actuating lug on said selector drum and a part arranged to actuate said selector-actuated element of the phonograph when force is applied to said first-mentioned part by said actuating lug, an abutment on said operating latch, a tripping latch pivotally connected to said support and having a working part normally engaging said abutment on the operating latch, the pivotal connection between said latches and said support comprising pivot pins on the support and open slots in the latches permitting free movement and ready removal of the latter, means for operating the tripping latch to disengage the same from said operating latch, and means for thereupon moving said operating latch into the path of said lug, the operating latch being movable by the lug to a position in which it is disengaged by the latter and in which the abutment thereon is automatically re-engageable by said working part on the tripping latch upon disengagement of the operating latch by said lug, said tripping latch being movable lineally by said operating latch, in shock

absorbing motion, upon re-engagement of said abutment with said working part.

3. In combination with a selector drum and a selector-actuated element of an automatic phonograph, selector mechanism comprising a support, an operating latch pivotally connected to said support and having a working part movable into the path of an actuating lug on said selector drum and a part arranged to actuate said selector-actuated element of the phonograph when force is applied to said first-mentioned part by said actuating lug, an abutment on said operating latch, a tripping latch pivotally connected to said support by a pin-and-slot connection, permitting lineal as well as pivotal movement of such latch, and having a working part normally engaging said abutment on the operating latch, spring means tending to draw said latches toward each other and to hold said working part in engagement with said abutment, means for operating the tripping latch to disengage the same from said operating latch, and means for thereupon moving said operating latch into the path of said lug, the operating latch being movable by the lug to a position in which it is disengaged by the latter and in which the abutment thereon is automatically re-engageable by said working part on the tripping latch upon disengagement of the operating latch by said lug, said tripping latch being movable linearly by said operating latch, in shock absorbing motion, upon re-engagement of said abutment with said working part.

4. In combination with a selector drum and a selector-actuated element of an automatic

phonograph, selector mechanism comprising a support, an operating latch pivotally connected to said support and having a working part movable into the path of an actuating lug on said selector drum and a part arranged to actuate said selector-actuated element of the phonograph when force is applied to said first-mentioned part by said actuating lug, an abutment on said operating latch, a tripping latch pivotally connected to said support and having a working part normally engaging said abutment on the operating latch, means for operating the tripping latch to disengage the same from said operating latch, means for thereupon moving said operating latch into the path of said lug, the operating latch being movable by the lug to a position in which it is disengaged by the latter and in which the abutment thereon is automatically re-engageable by said working part on the tripping latch upon disengagement of the operating latch by said lug, and shock-absorbing means, including a loose connection between said tripping latch and said support, permitting yielding movement of the tripping latch upon re-engagement of the operating latch therewith.
